(57) **CLAIM**

The ornamental design for a harness as shown and described.

DESCRIPTION

FIG. 1 is a front, right-side, top perspective view of a harness, showing the new design;

FIG. 2 is a front elevational view thereof;

FIG. 3 is a left-side elevational view thereof;

FIG. 4 is a rear elevational view thereof;

FIG. 5 is a right-side elevational view thereof; and,

FIG. 6 is a bottom plan view thereof.

The broken lines depict parts of the harness that form no part of the claimed design. The areas of grey shading depict areas having a contrasting visual appearance with the differently shaded areas.
